UNITED STATES PATENT OFFICE.

EMIL BERSBACH, OF BROOKLYN, NEW YORK.

DESIGN FOR A BRACKET.

SPECIFICATION forming part of Design No. 26,700, dated March 2, 1897.

Application filed January 19, 1897. Serial No. 619,813. Term of patent 7 years.

To all whom it may concern:

Be it known that I, EMIL BERSBACH, a citizen of the United States, residing at Brooklyn, in the county of Kings and State of New York, 5 have invented and produced a new and original Design for Brackets, of which the following is a specification, reference being had to the accompanying drawing, showing a part thereof.

10 The figure is a perspective view of the bracket, showing my design.

The leading features of my design are the bracket-arm merging in a simulation of a hand and the device made in imitation of a 15 scale held in the hand.

The bracket-body 10 simulates the sleeve of a coat, and has at one end a flange-like projection 11, while from the opposite end extends a projection 12, made to simulate a human hand, in which is held the device 13, 20 which is made in simulation of a scale, and the suspending-ring 14 of which is on the thumb of the hand.

What I claim is—

The design for a bracket herein shown and 25. described.

EMIL BERSBACH.
